US0D1072589S

(12) **United States Design Patent** (10) **Patent No.:** **US D1,072,589 S**
(45) **Date of Patent:** **** Apr. 29, 2025**

(54) **TRIMMER LINE**

(71) Applicant: **Jingqing Du**, Shiyian (CN)

(72) Inventor: **Jingqing Du**, Shiyian (CN)

(**) Term: **15 Years**

(21) Appl. No.: **29/921,641**

(22) Filed: **Dec. 18, 2023**

(51) LOC (15) Cl. **08-03**

(52) U.S. Cl.

USPC **D8/8**

(58) **Field of Classification Search**

USPC D8/8, 349, 354, 383
CPC A01D 34/416; A01D 34/4166; A01D
34/4168

See application file for complete search history.

(57) **CLAIM**

The ornamental design for a trimmer line as shown and described.

DESCRIPTION

FIG. 1 is a perspective view of my new design;

FIG. 2 is another perspective view thereof;

FIG. 3 is a front view thereof;

FIG. 4 is a rear view thereof;

FIG. 5 is a left side view thereof;

FIG. 6 is a right side view thereof;

FIG. 7 is an enlarged top view thereof; and,

FIG. 8 is an enlarged bottom view thereof.

The broken lines in the drawings depict portions of the trimmer line and form no part of the claimed design.

1 Claim, 8 Drawing Sheets
